FILM PROJECTING APPARATUS

Wilhelm Voigt, Wiesbaden-Biebrich, Germany,
assignor to Kalle & Co. Aktiengesellschaft,
Wiesbaden-Biebrich, Germany

Application July 16, 1936, Serial No. 90,842
In Germany July 16, 1935

4 Claims. (Cl. 88—18.4)

The present invention relates to film projecting apparatus.

In the usual film projecting apparatus, grippers employed for the intermittent feeding of the film are positively controlled by means of solid mechanical devices. As a consequence of this care must be taken when inserting the film in the projection window that the gripper is located in such position that it engages with a perforation of the film when the apparatus is set in operation. This requirement can, however, only be fulfilled sufficiently reliably with great difficulty. If the forwardly moving gripper, however, fails to engage the perforation of the film, damage to the latter is unavoidable.

Now it has been found that the film can be set forward with certainty without the danger of damage if the gripper, which may, for example, be made in fork shape, is fixed to the piston of a small pressure cylinder which is moved up and down along the film. The gas supply to this cylinder is regulated by suitable control members, for example the slide valve gear known in connection with steam engines, in such manner that the gripper engages with the perforation of the film during the time in which the cylinder moves in the direction of movement of the film. The cylinder piston must accordingly immediately before or at the commencement and immediately after or at the termination respectively of the cylinder movement, be moved towards the film and away from the film respectively. During the time in which the cylinder is moved in the opposite direction to the direction of movement of the film, the gripper releases the said film. By the employment of a gripper drive of this kind, it is rendered possible to insert the film in the projection window without particular precautions. If, for instance, the gripper does not immediately engage with a perforation of the film, then, because of the action of the elastic air buffer, the said gripper slides along the film without causing damage thereto until it engages with the perforation.

The movement of the pressure cylinder itself may be brought about in various ways. The said movement may also be controlled by means of gas pressure by arranging the cylinder on the piston of another pressure cylinder. The gas supply to the two cylinders may then take place through the same control member, so that the movements of the two pistons and consequently the horizontal and the vertical movements of the gripper, are positively coupled. A further possible arrangement for the movement of the pres-

sure cylinder containing the gripper piston is hereinafter described. The remaining movable parts of the apparatus, for example, guide drums and the like, are also preferably moved by gas pressure. In this way, almost noiseless running of the apparatus is obtained, which is very important, particularly for home kinematographs—especially in the projecting of sound films. As the driving gas it is preferable to employ compressed air, which can be produced by means of a simple bulb of rubber, bellows or the like. The supply of the compressed air to the apparatus is effected by means of thin rubber tubes. In this way a drive which is free from vibrations is rendered possible. It is naturally possible to substitute for the compressed air any other desired gas or even vapor for driving.

A constructional form of a film projecting apparatus according to the invention is illustrated by way of example in the accompanying drawings, in which:

Fig. 1 is a longitudinal section through the projecting apparatus,

Fig. 2 is a plan thereof,

Fig. 3 shows a front view of the apparatus with the casing removed, and

Fig. 4 shows a section taken on line 4—4 of Fig. 1.

Referring to the drawings:

Reference numeral 1 denotes a draw-off spool carrying the film which is to be projected. This spool is slidably mounted on the axle 17, which is journaled in a bore of the arm 18. The said arm is fixed to the baseboard 19 of the apparatus. The film 20 runs from the draw-off spool 1 over the toothed guide drum 2, meanwhile passing in front of and behind the said drum respectively over small guide rollers 21. The film then runs in a loop over the rounded off upper wall of the housing 43 and is thereupon led past the projecting window by means of the guide plate 22, the edges of which are turned over and form guide bars for the edges of the film. The gripper tooth 14 engages through a recess in the guide plate with the film perforation. The film is after the projection led back over the toothed drum 23 on to the winding up spool 24. The said spool is mounted so as to be slidably on the axle 17. The aforementioned toothed drums are mounted on an axle 53 rigidly with the worm wheel 25 and are driven by means of the worm 26. On the toothed drum 23 a cord pulley 27 is also arranged which drives the winding up spool 24 connected with the pulley 29 through the medium of a cord or chain 28. The turning knob 33

serves for overcoming the dead point when starting up the apparatus.

The objective employed is represented diagrammatically at 15. The reference numeral 16 denotes a lamp and 30 a reflector. 31 is a lens arranged in the mount 32, which lens throws the light emitted from the lamp in a bundle of rays on to the film located in the projection window. The lamp 16 is mounted in the holder 54. The 10 current supply leads 55 and 56 are separated from one another and from the supporting arm 57 by means of the insulating layers 58.

The driving mechanism proper is arranged on the bow 34 fixed to the baseboard. The driving 15 member is constituted by the cylinder 5 in which the piston 6 moves. The gas for driving the apparatus is led through the nozzle 35 into the slide valve housing 9 in which the slide valve 10 is arranged. In known manner, the said valve allows the driving gas to impinge alternately 20 through the openings 36 and 37 respectively on the two sides of the piston 6. The exhaust gas is discharged again in known manner through the openings 38 and 39 respectively. The piston 6 25 is connected by means of the piston rod 7 and the link 40 with the connecting rod 8 which is of frame-like form and drives the crank-shaft 3. From the said crank shaft 3 the slide valve 10, mounted on the link 42, is operated in known 30 manner by means of the eccentric 11 and the connecting rod 41 which is likewise constructed of frame-like form. The driving mechanism of the shaft 3 is accordingly identical with the usual drive of steam engines, so that further detailed 35 description is unnecessary. The shaft 3 is carried on the one side through the bow 34 and the wall of the housing 43 and is connected with the worm 26. On the other side, the shutter disc 4 is fixed on the axle.

40 The fork-shaped gripper 14 is fixed to the piston 13 by means of the piston rod 44. The piston 13 moves in the cylinder 12 and receives its driving gas through the conduits 45 and 59. The gas supply to the cylinder 12 is regulated by 45 means of the same slide valve which regulates the gas supply to the cylinder 5. The supply of the gas is effected through the bores or ports 46.

The cylinder 12 is fixed to the plate 47, which in 50 turn is fixed in the frame 48. At the upper end of this frame the axle 50 which carries a roller 51 is journalled in a projection 49. The said roller runs in a heart-like shaped curved guide 52 arranged in the shutter disc 4. During one 55 rotation of the curved guide, the gripper is moved once up and down. The curved guide is so adjusted that during the feeding of the film the picture is screened off by the vanes of the shutter.

The supply conduits for the driving gas to the 60 cylinder 12 are arranged by suitable location of the bores 46 in such manner that the piston 13 has been moved forward towards the film when the cylinder 12 moves downwards.

The operation of the apparatus illustrated in 65 the drawings is as follows:

At the beginning, the piston 6 is in its highest position in the cylinder 5. The shutter disc is so located on the axle 3 that the roll 51 is in the 70 position I relative to the curved guide 52. Owing to this position of the roll 51, the cylinder 12 is also in its highest position. The piston 13 is located on the right side of the cylinder 12 (see Fig. 1), so that the gripper 14 does not engage 75 with the perforation of the film. The operation

may be divided for explanation into the following four phases.

1. The nozzle 35 is connected by means of the slide valve 10 over the openings 36 and 45 with the cylinders 5 and 12, respectively, so that the stream of air fed through the nozzle 35 acts on the upper side of the piston 6 and the right side of the piston 13. The piston 13 moves to the left side, so that the gripper engages with the perforation of the film 20. During this time, the piston 6 moves somewhat down and the roll 51 moves from the position I to the position II. The cylinder 12 remains still in its initial position. The air in the lower part of the cylinder 5 and the left part of the cylinder 12 escapes through 15 the openings 59 and 37, respectively, which are connected in this phase with the outlet opening 39. The shutter is open during this phase.

2. The piston 6 moves further downward until it has reached its lowest position. Owing to 20 that movement, the roll 51 moves from the position II to the position III, and the cylinder 12 moves down. The piston 13 remains in the position it has assumed during phase 1, so that the film is drawn off. The shutter is closed during 25 this phase.

3. The slide valve changes its position relative to the openings of the slide valve housing so that the air is led from the nozzle 35 over the opening 37 on the lower side of the piston 6. The 30 room of the cylinder 5 above the piston 6 is connected over the opening 36 with the outlet opening 38. Simultaneously, the openings 45 and 59 are connected with the openings 38 and 35, respectively. The piston 13 is pressed to the right 35 so that the gripper releases the perforation. During this time, the piston 6 moves somewhat upward and the roll 51 moves from the position III to the position IV. The cylinder 12 remains still in the position it has assumed during phase 2. 40 The shutter is open during this phase.

4. The piston 6 moves further upward until it has reached its highest position and the roll 51 moves from the position IV to the position I. Owing to this movement of the roll 51, the cylinder 12 rises. At the end of this phase, during 45 which the shutter is closed, all parts have again reached their initial position.

I claim:

1. Film projecting apparatus, comprising a film 50 guiding device containing a projecting window, an objective before the said window and a lamp behind the window, a driven axle above the said window, a shutter disc on this axle, the vanes of the said shutter disc being able to cover the 55 said projecting window, a heart-like shaped groove in the said shutter disc, a roller which slides in the said groove and a rod connected with the said roller, the groove being so adjusted that during one rotation of the disc the rod is moved once up and down, a cylinder fixed at the free end of the said rod beneath the said projecting window so that the axis of the cylinder is vertical to the said shutter disc, a piston 60 slidably arranged in the said cylinder, two openings in the said cylinder near the ends of the cylinder, a rod on the said piston penetrating the base plate of the said cylinder which is located opposite to the said film guiding device, a fork-shaped gripper fixed to the said piston rod, a 65 slide valve serving for regulating the gas supply to the said cylinder, which valve is driven by the said axle and so adjusted that the valve allows the gas to flow into the opening of the cylinder near the gripper side of the said piston, 70

75

when the cylinder moves upward, and that the valve allows the gas to flow into the other opening of the cylinder when the cylinder moves downward.

5 2. A motion picture projection apparatus, comprising a film guiding device containing a window, means for projecting a film in combination with the said window, a pressure cylinder arranged near the said guiding device and beneath

10 the said projecting window with its axis perpendicular to the plane of the said projecting window, a piston slidably arranged in the interior of the said cylinder, a rod on the said piston penetrating one of the base plates of the said cylinder through a bore, a gripper fixed on the free end of the said piston rod, the cylinder being located at such a distance from the said guiding device that the gripper in the one end position of the piston can engage with the perforation of a

15 film arranged in the said guiding device, means serving for moving the cylinder up and down parallel to the said guiding device, and means for alternately leading a gas onto the sides of the said piston.

20 3. A motion picture projecting apparatus, comprising a film guiding device containing a projecting window, means for projecting a film in combination with the said window, a pressure cylinder arranged near the said guiding device and beneath the said projecting window with its axis perpendicular to the plane of the said projecting window, a piston slidably arranged in the interior of the said cylinder, two openings in the wall of the said cylinder serving for leading a gas onto the sides of the said piston, a rod on the said piston penetrating one of the base plates of the said cylinder 25 through a bore, a fork-shaped gripper fixed on the said piston rod, the cylinder being located at such a distance from the said guiding device that the gripper in the one end position of the piston can engage with the perforation of a film arranged in the said guiding device, means serving for moving the cylinder up and down parallel to the said guiding device, a slide valve connected with the openings of the said cylinder adapted for regulating the gas supply to the cylinder, the said valve being coupled in such a way with the cylinder moving means that the valve allows the gas to flow into the opening of the cylinder near the gripper side of the said piston when the cylinder moves upward, and that the 30 valve allows the gas to flow into the other opening of the cylinder when the cylinder moves downward.

guiding device that the gripper in the one end position of the piston can engage with the perforation of a film arranged in the said guiding device, means serving for moving the cylinder up and down parallel to the said guiding device, 5 and a valve connected with the said cylinder adapted for regulating an alternating gas supply to the said openings of the cylinder.

4. A film projecting apparatus, comprising a film guiding device containing a projecting window, an objective before the said window, a lamp behind the window, a pressure cylinder arranged near the said guiding device and beneath the said projecting window with its axis perpendicular to the plane of the said projecting window, a piston 10 slidably arranged in the interior of the said cylinder, two openings in the wall of the said cylinder serving for leading a gas onto the sides of the said piston, a rod on the said piston penetrating one of the base plates of the said cylinder 15 through a bore, a fork-shaped gripper fixed on the said piston rod, the cylinder being located at such a distance from the said guiding device that the gripper in the one end position of the piston can engage with the perforation of a film arranged in the said guiding device, means serving for moving the cylinder up and down parallel to the said guiding device, a slide valve connected with the openings of the said cylinder adapted for regulating the gas supply to the cylinder, the said valve being coupled in such a way with the cylinder moving means that the valve allows the gas to flow into the opening of the cylinder near the gripper side of the said piston when the cylinder moves upward, and that the 20 valve allows the gas to flow into the other opening of the cylinder when the cylinder moves downward.

WILHELM VOIGT.
